UNITED STATES PATENT OFFICE.

WALTER D. SCHMITS, OF NEW YORK, N. Y.

CHAIR-SEAT.

1,184,265.

Specification of Letters Patent. Patented May 23, 1916.

Application filed June 5, 1915. Serial No. 32,279.

To all whom it may concern:

Be it known that I, WALTER D. SCHMITS, a citizen of the United States, residing at New York city, county and State of New 5 York, have invented certain new and useful Improvements in Chair-Seats, of which the following is a specification.

This invention relates to a chair seat and more particularly to novel and effective 10 means for permitting the renewal of a worn seat in a quick and simple manner.

In the accompanying drawing, Figure 1 is a cross section through part of a chair seat embodying my invention; Fig. 2 a similar section through part of the detached seat, and Fig. 3 a plan view thereof.

The numeral 10 indicates the suitably shaped seat frame of a chair or similar article of furniture. At its upper face, 20 frame 10 is provided with a continuous groove 11 that extends in proximity to the inner wall 12 of said frame, thereby leaving a ledge 13 between said groove and inner frame wall. Ledge 13 is provided with a 25 rounded top 14 that constitutes a support for the chair bottom 15 as will hereinafter be more fully explained.

The chair bottom consists of interwoven cane or other suitable material and is 30 permanently attached to a continuous metal frame or carrier 16 of a size and contour to snugly fit into the groove 11. The carrier 16 consists of a pair of nested, substantially U-shaped metallic rings or grooved binding 35 members 17, 18 between which the bottom 15 is firmly clamped in position, for which purpose these rings are united by rivets or similar fastening elements 19 the upper ends of which are countersunk within the groove 40 of the upper ring 17. Intermediate the rivets 19, rings 17, 18 are perforated for the passage of screws 20 the heads of which are likewise countersunk within said groove, and by means of which the chair bottom-carrying frame 16 is secured to the seat frame 45

10. The carrier 16 is hidden from view by a covering frame 21 that overlaps said carrier, the general configuration of the covering frame corresponding to that of the seat frame. The covering frame is shown to be 50 made wedge-shaped in cross section, its upper inclined face gradually approaching its lower horizontal face from the outer toward the inner edge of the frame. The covering frame 21 is of such a thickness that 55 the inclined surface thereof tapers toward the rounded top 14 of ledge 13 around which the chair bottom 15 is laid as clearly illustrated in Fig. 1. In this way the chair bottom merges into the gradually ascending 60 top of the covering frame so that not only a neat finish is presented but the seat is rendered more comfortable for the occupant. The covering frame 21 is held in position by a suitable number of screws 22 passing 65 upwardly through the seat frame into the covering frame.

If it becomes necessary to replace a worn chair seat, the covering frame 21 is removed, and the screws 20 are unscrewed, whereupon 70 the frame 16 carrying the worn bottom 15 may be withdrawn. Another frame 16 provided with a new chair bottom 15 is then inserted into the groove 11 and is secured in place by the screws 20, whereupon the 75 covering frame is re-attached to the seat frame 10. In this way, the renewal of a worn chair seat may be effected by unskilled help in a quick and simple manner.

I claim:

As a new article of manufacture, a chair bottom, an encompassing binding frame consisting of two channel-shaped nested members receiving the perimeter of the chair bottom therebetween, and fastening means 85 permanently connecting the channel-shaped members to each other and securing the chair bottom to said members.

WALTER D. SCHMITS.
